CHRISTOPHER COLLARO, OF PECKHAM, LONDON, ENGLAND, ASSIGNOR TO HENRY DEVELOPMENTS LIMITED, OF LONDON, ENGLAND

TALKING MACHINE

Application filed November 17, 1930, Serial No. 496,277, and in Great Britain March 13, 1930.

This invention relates to talking machines.

The object of the present invention is to provide an improved machine for recording and reproducing sound by the employment of discs in which the sound groove is arranged to travel at a constant linear speed with respect to the recording or producing stylus.

According to the invention a drum associated with means adapted to ensure its rotation at a constant speed is provided and to the drum is secured one end of a flexible member adapted to be wound on to or off the drum, the other end of the flexible member being secured to a fusee associated with a second fusee in such manner that both fusees rotate at equivalent speeds, one end of a second flexible member being connected with the smaller end of the second fusee and with a weight or the like means for securing a constant driving effort, and a driving connection is provided between the fusees and the turntable.

As will be understood, with such an arrangement the rotation of the fusees will be such that while one wire or flexible member is being unwound from the fusee with which it is associated, the other is being wound on to its associated fusee.

Further, in accordance with the invention, means are provided whereby upon rotation of the drum in order to raise the weight, the driving connections between the drum and the means provided for securing a constant speed, and between the fusees and the turntable are released.

Conveniently, more particularly in connection with machines intended for recording, the driving connection between the fusee and the turntable is also arranged to cause the turntable, the frame carrying the same and the fusees to travel in a rectilinear path with respect to the stylus.

In one construction in accordance with the invention, a drum is connected through suitable reduction gearing with a governor adapted to ensure a constant speed of operation of

the drum, and with the drum is connected one end of a wire or flexible member adapted to be unwound therefrom by rotation of a fusee, to the larger end of which the other end of the wire or flexible member is connected, and the said fusee is coaxially mounted upon a shaft with a second fusee in such manner that both fusees rotate at the same angular velocity and to the second fusee is connected at the smaller end thereof one end of a second wire or flexible member which is passed over a pulley and connected at its other end with a weight.

Between the fusees and the turntable a positive driving connection is provided. For instance, with the fusees may be associated a toothed wheel adapted through suitable gearing to form a driving connection with the spindle to which the turntable is secured.

Particularly in the case of machines designed for recording, the housing or frame for the fusees and the drum is slidably arranged on a support and the spindle for the turntable or a spindle from which motion is imparted thereto may in such case be arranged in driving connection with a worm whereby the housing or frame will be moved in a rectilinear path with respect to the stylus at a pre-arranged speed to give the number of cuts per inch required in the record.

With the device above described, in winding up the drum the flexible member, connecting the drum with one of the fusees, is drawn from the said fusee and wound upon the drum, the connections between the governor and the drum, and between the fusees and the turntable being thrown out of action during this operation, while the wire or the like connected with the second fusee will be wound on to the same, thus raising the weight.

At any required position of the recording head the winding is stopped and the weight is allowed to operate to rotate the turntable, a constant linear speed being maintained throughout the operation by reason of the

fact that the wire connected with the drum is arranged to operate at a constant speed, being wound at a constant linear rate on to one fusee thus causing the fusee to rotate at a progressively increasing rate and consequently causing the turntable to revolve at a progressively increasing angular velocity.

The invention will be described further in detail with reference to the accompanying drawings, in which:

Figure 1 is a view in elevation of a machine in accordance with the invention, and

Figure 2 is a corresponding plan view thereof; while

Figure 3 is a view in section of a detail and

Figure 4 is a sectional plan view of the same.

In the drawings, 1 represents the bed plate of the machine provided with guides 2 for the saddle or carriage 3 mounted thereon. On the carriage is arranged the drum 4 mounted on the spindle 5 engaging in bearings in the side members 6 and 6a provided on the carriage. On the spindle in question is also mounted a spur wheel 7 and a worm wheel 8, the former being arranged to engage with the pinion 9 which is removably mounted on the spindle 10 and is provided with a handle 11 and a ratchet 12 adapted to engage the pawl 13 with which is associated the spring 14. The worm wheel 8 is in engagement with the worm 15 rotatably mounted on the spindle 16 and provided with a dog clutch element 17 adapted to engage the dog clutch element 18, the teeth of these elements being arranged so that on the rotation of the drum in the direction of the arrow in Figure 1, the driving connection between the dog clutch elements will be interrupted and the worm wheel 19, which is associated with the dog clutch element 18 will not, in such case, operate the worm 20 the pivots 21, 21a of which are arranged in bearings 22 and 22a and the associated worm wheel 23 which is in engagement with the worm 24 on the spindle of the centrifugal governor 25, the pivots of which 26 and 26a are arranged in bearings 27 and 27a.

With the end plate 29 of the governor is arranged to co-operate a brake member in the form of an annulus 30 which has a gimbal mounting, being provided with pins 31 engaged in the arm 32 connected to the bracket 33 and provided with an adjusting screw 34.

The governor in question operates to ensure that the drum 4 will rotate at a constant speed as the wire rope 35 is unwound from it and wound upon the fusee 36 which, together with the fusee 37 and the worm wheel 38, is mounted on the spindle 39, the ends of which are engaged in bearings 40 and 40a provided in the brackets 41 and 41a.

The two fusees and the associated worm wheel are rotatable at a varying angular ve-

locity corresponding with the conicity of the fusees by unwinding from the fusee 37 a wire rope 42 which passes over the blocks 43 and 44, to the latter of which is connected a weight 45.

The worm wheel 38 is in engagement with the worm 46 mounted on the spindle 47 on which and on the same spindle rotatable with the said worm is arranged a worm 48 in engagement with the worm wheel 49 rotatably mounted on a sleeve 50 mounted in the bearing member 51 rigidly connected with the saddle 3. The sleeve 50 is provided internally with a screw-thread engaging the lead screw 52 which is mounted in brackets 53 and 53a on the bed plate of the machine so that by its rotation the saddle is caused to travel on the guides on the bed plate.

The worm 46 is provided with a one-way dog clutch member 54 engaging a correspondingly formed dog clutch member 55 which is provided with a key-way 56 engaging the Woodruff keys 57 which also engage the sleeve 58 on which the helical wheel 59 is formed. This wheel engages a corresponding helical wheel 60 engaged in a collar 61 supported on a collar 62 rigidly connected with the spindle 63 of the turntable 64 on which the mould containing the wax for forming the record matrix 65 will be supported and moved relatively to the cutter 66. The wheel 60 and its collar 61 is capable of a limited degree of rotary motion about the spindle, the driving connection between it and the spindle being constituted by a strip of spring steel 67 engaged between the pins 68 and 68a provided on the collar.

The purpose of this connection between the driving means and the turntable is to prevent "watering", that is to say, an effect which is liable to arise in consequence of the varying resistance to rotation of the turntable under the action of the cutter operating upon the matrix.

The operation of the apparatus is as follows:

The cutter, which will normally be a device adapted to be operated by sounds through suitable electrical amplifying devices, is secured in known manner to a fixed head and the table is traversed with respect to the cutter.

Rotation of the table is secured by rotating the drum 4 through the intermediary of the pinion 9 and the toothed wheel 7 so as to wind on the drum the wire rope 35 off the fusee 36.

During this operation owing to the over-running of the dog clutch members 17 and 18, the governor will not be operated while, owing to the over-riding of the dog clutch members 54 and 55, rotation of the turntable 64 will be prevented.

The winding off of the wire rope from the fusee 36 will cause the wire rope 42 to be

wound on to the fusee 37, the weight 45 being thereby raised. The winding operation is carried out until the carriage or saddle 3 is brought into a definite position on the bed 1, 5 a scale on the former and an index on the latter being provided to enable the correct position to be determined.

When the saddle has been brought into the correct position the cutting of the matrix is 10 commenced by removing the handle 11 and its associated ratchet 12 from the spindle 10 and thus allowing the weight 45 to descend whereby the rope 42 will be unwound from the fusee 37 at a constant linear speed with 15 the result that the fusees will rotate at a varying angular velocity, which will increase as the turntable is moved relatively to the head carrying the cutter to bring the cutter towards the centre of the matrix in consequence 20 of the rotation of the worm 48 rotat- ing the worm wheel 49, the sleeve 50 of which constitutes a nut operating in conjunction with the lead screw 52. The rotation of the worm wheel 46 also causes the same to drive 25 through the toothed wheels 59 and 60, the spindle 63 of the turntable at a varying angular velocity which increases as the cutter app- roaches the centre of the matrix.

In conclusion, it may be pointed out that 30 the invention extends to sound recording or reproducing machines generally in which the stylus carrier is stationarily secured and the member carrying the record disc or the like is moved bodily relative thereto irrespective 35 of the means for securing rotation of the turntable or the equivalent.

The expression "machine for use in the reproduction of sound" as used in the appended claims is to be interpreted as including 40 machines designed to be influenced by sound and to produce a sound record and machines designed to operate upon sound records and thereby function as talking machines. The invention, however, is mainly concerned with 45 machines designed for use in the production of sound records.

I claim:

1. A machine for use in the reproduction of sound comprising a rotatably mounted 50 drum, a rotatably mounted fusee, a flexible member secured at one of its ends to the drum and at its other end to the fusee adapted upon rotation of the drum in one direction to be unwound from the drum on to the 55 fusee and upon rotation of the drum in the opposite direction to be unwound from the fusee on to the drum, a governor in driving engagement with the drum adapted to ensure its rotation at a constant angular velocity, a second fusee associated with the first-mentioned fusee 60 adapted to rotate at an equivalent speed to the first-mentioned fusee, a turntable in driving engagement with the fusees upon which a record disc is adapted to be supported, a stylus adapted to operate upon the sound record disc and to travel in a spiral path relative thereto, a second flexible member connected at one of its ends with the second-mentioned fusee, a weight connected with the other end of the second flexible member adapted to provide a constant driving effort whereby the said spiral path may be caused to travel at a constant linear speed relative to the stylus.

upon the sound record disc and to travel in a spiral path relative thereto, a second flexible member connected at one of its ends with the second-mentioned fusee, and driving means connected with the other end of the 70 second flexible member adapted to provide a constant driving effort whereby the said spiral path may be caused to travel at a constant linear speed relative to the stylus.

2. A machine for use in the reproduction 75 of sound comprising a rotatably mounted drum, a rotatably mounted fusee, a flexible member secured at one of its ends to the drum and at its other end to the fusee adapted upon rotation of the drum in one direction to be unwound from the drum on to the fusee and upon rotation of the drum in the opposite direction to be unwound from the fusee on to the drum, a governor in driving engagement with the drum adapted to ensure 80 its rotation at a constant angular velocity, a second fusee associated with the first-mentioned fusee adapted to rotate at an equivalent speed to the first-mentioned fusee, a turntable in driving engagement with the fusees 85 upon which a record disc is adapted to be supported, a stylus adapted to operate upon the sound record disc and to travel in a spiral path relative thereto, a second flexible member connected at one of its ends with the second-mentioned fusee, and a weight connected with the other end of the second flexible member adapted to provide a constant driving effort whereby the said spiral path may be caused to travel at a constant linear speed relative to the stylus.

3. A machine for use in the reproduction 95 of sound comprising a rotatably mounted drum, a rotatably mounted fusee, a flexible member secured at one of its ends to the drum and at its other end to the fusee adapted upon rotation of the drum in one direction to be unwound from the drum on to the fusee and upon rotation of the drum in the opposite direction to be unwound from the fusee on to the 100 drum, a governor in driving engagement with the drum adapted to ensure its rotation at a constant angular velocity, a second fusee 105 associated with the first-mentioned fusee adapted to rotate at an equivalent speed to the first-mentioned fusee, a turntable in driving engagement with the fusees upon which a record disc is adapted to be supported, a stylus adapted to operate upon the sound record disc and to travel in a spiral path relative thereto, a second flexible member connected at one of its ends with the second-mentioned fusee, a weight connected with the other end of the second flexible member adapted to provide a constant driving effort 110 whereby the said spiral path may be caused to travel at a constant linear speed relative to the stylus, means adapted to rotate the drum in order to raise the weight, and means adapted upon rotation of the drum in order 115 120 125 130

to raise the weight to release the driving engagement between the drum and the governor, and the driving engagement between the fusees and the turntable.

- 5 4. A machine for use in the reproduction of sound comprising a rotatably mounted drum, a rotatably mounted fusee, a flexible member secured at one of its ends to the drum and at its other end to the fusee adapted upon rotation of the drum in one direction to be unwound from the drum on to the fusee and upon rotation of the drum in the opposite direction to be unwound from the fusee on to the drum, a governor in driving engagement with the drum adapted to ensure its rotation at a constant angular velocity, a second fusee associated with the first-mentioned fusee adapted to rotate at an equivalent speed to the first-mentioned fusee, a turn-table in driving engagement with the fusees upon which a record disc is adapted to be supported, a stylus adapted to operate upon the sound record disc and to travel in a spiral path relative thereto, a second flexible member connected at one of its ends with the second-mentioned fusee, driving means connected with the other end of the second flexible member adapted to provide a constant driving effort whereby the said spiral path may be caused to travel at a constant linear speed relative to the stylus, and means adapted upon rotation of the fusees to cause the turntable and the fusees to travel in a rectilinear path with respect to the stylus.
- 20 5. A machine for use in the reproduction of sound comprising a rotatably mounted drum, a rotatably mounted fusee, a flexible member secured at one of its ends to the drum and at its other end to the fusee adapted upon rotation of the drum in one direction to be unwound from the drum on to the fusee and upon rotation of the drum in the opposite direction to be unwound from the fusee on to the drum, a governor in driving engagement with the drum adapted to ensure its rotation at a constant angular velocity, a second fusee associated with the first-mentioned fusee adapted to rotate at an equivalent speed to the first-mentioned fusee, a turn-table in driving engagement with the fusees upon which a record disc is adapted to be supported, a stylus adapted to operate upon the sound record disc and to travel in a spiral path relative thereto, a second flexible member connected at one of its ends with the second-mentioned fusee, driving means connected with the other end of the second flexible member adapted to provide a constant driving effort whereby the said spiral path may be caused to travel at a constant linear speed relative to the stylus, and means adapted upon rotation of the fusees to cause the turntable and the fusees to travel in a rectilinear path with respect to the stylus.
- 25 6. A machine for use in the reproduction of sound comprising a rotatably mounted drum, a rotatably mounted fusee, a flexible member secured at one of its ends to the drum and at its other end to the fusee adapted upon rotation of the drum in one direction to be unwound from the drum on to the fusee and upon rotation of the drum in the opposite direction to be unwound from the fusee on to the drum, a governor in driving engagement with the drum adapted to ensure its rotation at a constant angular velocity, a second fusee associated with the first-mentioned fusee adapted to rotate at an equivalent speed to the first-mentioned fusee, a turn-table in driving engagement with the fusees upon which a record disc is adapted to be supported, a stylus adapted to operate upon the sound record disc and to travel in a spiral path relative thereto, a second flexible member connected at one of its ends with the second-mentioned fusee, driving means connected with the other end of the second flexible member adapted to provide a constant driving effort whereby the said spiral path may be caused to travel at a constant linear speed relative to the stylus, and means adapted upon rotation of the fusees to cause the turntable and the fusees to travel in a rectilinear path with respect to the stylus.
- 30 7. A machine for use in the reproduction of sound comprising a bed plate, guides secured to the bed plate, a carriage mounted upon the bed plate slidably engaging with the guides, a drum rotatably mounted in the carriage, a fusee rotatably mounted in the carriage, a flexible member secured at one of its ends to the drum and at its other end to the fusee adapted upon rotation of the drum in one direction to be unwound from the drum on to the fusee and upon rotation of the drum in the opposite direction to be unwound from the fusee on to the drum, a governor in driving engagement with the drum adapted to ensure its rotation at a constant angular velocity, a second fusee co-axially mounted in the carriage with the first-mentioned fusee adapted to rotate at an equivalent speed to that of the first-mentioned fusee, a turn-table in driving engagement with the fusees upon which a record disc is adapted to be supported, a stylus adapted to operate upon the sound record disc and to travel in a spiral path relative thereto, a second flexible member connected at one of its ends with the second-mentioned fusee, a weight connected with the other end of the second flexible member adapted to provide a constant driving effort whereby

of sound comprising a rotatably mounted drum, a rotatably mounted fusee, a flexible member secured at one of its ends to the drum and at its other end to the fusee adapted upon rotation of the drum in one direction to be unwound from the drum on to the fusee and upon rotation of the drum in the opposite direction to be unwound from the fusee on to the drum, a governor in driving engagement with the drum adapted to ensure its rotation at a constant angular velocity, a second fusee associated with the first-mentioned fusee adapted to rotate at an equivalent speed to the first-mentioned fusee, a turn-table in driving engagement with the fusees upon which a record disc is adapted to be supported, a stylus adapted to operate upon the sound record disc and to travel in a spiral path relative thereto, a second flexible member connected at one of its ends with the second-mentioned fusee, a weight connected with the other end of the second flexible member adapted to provide a constant driving effort whereby the said spiral path may be caused to travel at a constant linear speed relative to the stylus, means adapted to rotate the drum in order to raise the weight, means adapted upon rotation of the drum in order to raise the weight to release the driving engagement between the drum and the governor, and the driving engagement between the fusees and the turntable, and means adapted upon rotation of the fusees to cause the turntable and the fusees to travel in a rectilinear path with respect to the stylus.

35 7. A machine for use in the reproduction of sound comprising a bed plate, guides secured to the bed plate, a carriage mounted upon the bed plate slidably engaging with the guides, a drum rotatably mounted in the carriage, a fusee rotatably mounted in the carriage, a flexible member secured at one of its ends to the drum and at its other end to the fusee adapted upon rotation of the drum in one direction to be unwound from the drum on to the fusee and upon rotation of the drum in the opposite direction to be unwound from the fusee on to the drum, a governor in driving engagement with the drum adapted to ensure its rotation at a constant angular velocity, a second fusee co-axially mounted in the carriage with the first-mentioned fusee adapted to rotate at an equivalent speed to that of the first-mentioned fusee, a turn-table in driving engagement with the fusees upon which a record disc is adapted to be supported, a stylus adapted to operate upon the sound record disc and to travel in a spiral path relative thereto, a second flexible member connected at one of its ends with the second-mentioned fusee, a weight connected with the other end of the second flexible member adapted to provide a constant driving effort whereby

the spiral path in the record disc may be caused to travel at a constant linear speed relative to the stylus, means adapted to rotate the drum in order to raise the weight,
5 means adapted upon rotation of the drum in order to raise the weight to release the driving engagement between the drum and the governor, and the driving engagement between the fuses and the turntable, and driving means adapted to be actuated by rotation of the fuses in order to cause the carriage, the turntable, and the fuses associated therewith, to travel in a rectilinear path with respect to the stylus.

15 In testimony whereof I have signed my name to this specification.

CHRISTOPHER COLLARO.
